UNITED STATES PATENT OFFICE.

THADDEUS J. BARROW, OF RIVERSIDE, CALIFORNIA.

NEWSPAPER HOLDER.

Application filed May 11, 1921. Serial No. 468,691.

To all whom it may concern:

Be it known that I, THADDEUS J. BARROW,
a citizen of the United States, residing at
Riverside, in the county of Riverside and
State of California, have invented new and
useful Improvements in Newspaper Holders,
of which the following is a specification.

This invention has for its object to provide an improved newspaper holder for holding 10 a volume of newspapers or other periodicals in the order in which they are published, so as to render them conveniently accessible for reference.

Another object is the provision of a novel type of support for the paper holders, whereby any one of the series of the holders is rendered readily accessible for reference to the newspaper secured therein.

With this and other objects in view, the invention consists in the novel construction, combination and arrangement of parts as will be hereinafter specifically described, claimed and illustrated in the accompanying drawings, in which:

25 Figure 1 represents a perspective view of the improved newspaper holder and support therefor.

Figure 2 represents a similar view, showing the pivoted board in lowered position.

30 Figure 3 represents an enlarged perspective view of the newspaper holder detached from the support.

Figure 4 represents a perspective view of the newspaper binding strip detached.

35 Figure 5 represents a fragmentary transverse sectional view through a newspaper showing the binding strip in detail.

Figure 6 represents a fragmentary perspective view of the binding strip, showing the attaching ear, and

Figure 7 represents an end elevation of a modified type of the newspaper holder and support, therefor.

Referring to the drawings in detail, where in similar reference numerals designate corresponding parts throughout the several views, the numeral 5 indicates a supporting table or desk, the inclined top of which constitutes a support for the lower newspaper holder. A pair of upstanding arms 8 are fastened adjacent the rear or

arms 8 are fastened adjacent the rear of upper edge of the inclined top 6 and pivotally secures a supporting plate or board 9 in spaced relation to the inclined top 6. A pair of supporting legs 10 are secured

to the front edge of the board 9 and are adapted to engage the inclined top 6 to support the board 9 in spaced relation thereto. The board is supported in an elevated position by a brace 11. A newspaper holder 12, identical in construction to the holder 7, is supported centrally of the supporting board 9. 60

Each newspaper holder comprises a pair of angular straps 13, which are secured centrally of the longitudinal edges of either the board 9 or top 6 and pivotally secure a rectangular frame 14. A pair of rods 15 are rigidly secured between the longitudinal members of the rectangular frame 14 at adjacent ends of the latter, and a removable pin 16, having a headed upper terminal 17 is removably positioned through transversely alined apertures formed centrally of the longitudinal members of the frame 14. The pin 16 passes through the center of the bow spring 18, the free ends of which are engaged with the upper longitudinal member by the frame 14, and the medial portion of which is adapted to engage the newspaper, or other articles, secured in the holder for compactly holding them.

Binding strips 19, constructed of sheet metal and substantially U-shape in cross section, are adapted to receive the folded portion of the newspaper 20 and the parallel members of the strip 19 are formed with apertures 21, through which is passed a cord or other flexible member 22, which is also passed through apertures formed in the newspaper to secure the latter in position in the binding strips. The strip 19 is formed centrally with a laterally projecting ear 23, having an aperture 24 therein to receive the removable pin 16, whereby the binding strip is removably secured in position in the frame 14. Adjacent its ends the binding strip 19 is provided with laterally projecting ears 25, having recesses 26 therein extending in parallel relation to the strip 19 and adapted to receive the relatively stationary rods 15, whereby the top and bottom edge portions of the newspaper are held in position in the frame 14.

In use, the newspaper holder 7, supported upon the top 6 may be utilized for holding the issue of one newspaper and the holder 12 supported upon the pivoted board 110

9 is utilized for holding the issues of another newspaper. The newspapers 20 are compactly held in the frames 14 by the bow springs 18, and the frame 14 may be swung 5 to either side to render the newspaper readily accessible. When it is desired to refer to a certain newspaper in the group positioned in the holder 7, the pivoted board 9 is swung to open position and is held in 10 that position by the brace 11. However, when it is desired to refer to a certain newspaper held in the upper holder 12, the brace 11 is removed and the board 9 is swung to closed position, thereby moving 15 the holder 12 and newspapers positioned therein into intermediate position for reference.

In the modification of the invention illustrated in Figure 7 the table or desk 5^a is 20 provided with oppositely inclined top sections 6, to which are pivotally secured the pivoted boards 9, which are identical in construction to the boards designated by the corresponding numerals in the other figures 25 in the drawings.

The newspaper holders 7 and 12 are supported in position upon the top section 6 and board 9 in the manner hereinbefore described.

30 I claim as my invention:

1. A device of the character described including a pivoted frame, rods secured in said frame, newspaper binding strips, ears carried by said strips, certain of said ears 35 having slots therein and the other ears having an aperture therethrough, the slotted ears being detachably engaged by the rods, and a pin positioned through the apertured

ear securing the strips in position in the frame. 40

2. The combination with a pivotally mounted frame, of a movable binding strip, an ear carried by said strip, a pin positioned through the frame and the ear for securing the strip in position, rods secured in the frame which rods are detachably connected to said binding strip, and spring means arranged in the frame and engaging the ear to secure the strip against accidental movement. 45

3. The combination with a pivotally mounted frame, of a relatively movable binding strip, an ear carried by said strip, a removable pin positioned through the frame and ear to secure the strip in position, rods secured in the frame which rods are detachably connected to said binding strip, and a spring receiving the pin and engaging the frame and ear to retain the strip against movement. 50

4. A device of the character described including a pivoted frame, rods secured in said frame, newspaper binding strips, ears carried by said strips, certain of said ears having slots therein and the other ears having an aperture therethrough, the slotted ears being detachably engaged by the rods, a pin positioned through the apertured ear securing the strips in position in the frame, and a spring receiving the pin and engaging the frame and ear to retain the strip against movement. 60

In testimony whereof I have signed my name to this specification.

THADDEUS J. BARROW.
